SCREW PLUG CAP AND METHOD OF FORMING THE SAME

Elvin A. Taylor, Plymouth, Mich., assignor to Plymouth
Stamping Company, Plymouth, Mich., a corporation
of Michigan

Application May 12, 1954, Serial No. 429,338

2 Claims. (Cl. 220—39)

The invention relates to screw caps and more particularly to that type used for retaining a liquid within a container while at the same time providing a vent for the passage of air. One use for such construction is in connection with a master cylinder of a hydraulic brake system.

It is the object of the invention to obtain a construction that can be manufactured at relatively small cost and which provides the necessary vent passage and at the same time forms an effective baffle for preventing outward passage therethrough of liquid.

It is a further object to obtain a construction having various additional advantageous features.

With these objects in view the invention consists in the construction and method of forming the same as herein-after set forth.

In the accompanying drawings:

Fig. 1 is a side elevation of my improved screw plug cap;

Figs. 2 and 3 are respectively a top plan view and bottom view thereof;

Fig. 4 is a central longitudinal section on line 4—4, Fig. 3;

Fig. 5 is an enlarged view of a portion of Fig. 4 after the formation of the screw threads thereon;

Figs. 6 and 7 illustrate successive steps in the formation of one of the cup members;

Fig. 8 is a plan view of a modified construction of plug cap;

Fig. 9 is a side elevation thereof;

Fig. 10 is a perspective view.

The plug cap comprises essentially two cupped sheet metal stampings A and B having a central flange union C with each other. The member A has the cupped portion A' thereof polygonal, preferably square as shown in Fig. 2. A flange A² extends radially from the open end of the cup and is of sufficient extent to form the union C as later described. The member B is formed with a cylindrical cupped portion B' with a radial flange B² at its open end. In the stamping of this member it is first formed with an imperforate slightly concaved bottom portion B³ connected to the cylindrical side by a rounded portion B⁴. The flange B² which is more or less irregular in shape as first formed is then trimmed to a circular contour of proper diameter and simultaneously with this trimming operation portions of the bottom B³ are struck out in a downward direction, being severed at the outer edge to form vent slits B⁵ with baffle portions B⁶ beneath the same. The cylindrical cup portion B' is then screw threaded preferably by a rolling thread forming operation which, however, cannot extend completely to the flange B². These three operations are all that are required to finish the member B.

To complete the assembly the flange A² of the member A which has been trimmed to a circular form and the proper diameter is peened or turned down over the periphery of the flange B² and then inward beneath said flange. Thus, the union C forms a radially outwardly extending portion which is equal in thickness to three times the gage of the sheet metal. The inturned portion A³ of the flange A² will thus cover any unthreaded portion or imperfectly threaded portion of the cylindrical cup B' so that the exposed threads will be full throughout

2

their length. The member A is provided at any convenient point with a punched air vent aperture A⁴.

With the construction as described, the punched out portions B⁶ form effective shields for preventing passage of liquid upward into the hollow cap but if any liquid does pass therewithin it will quickly drain out by reason of the convex upper face of the bottom portion B³. The rounded portion B⁴ forms a pilot for guiding the threads of the cap into engagement with those of the casing with which it is engaged. Thus, the cap is easily engaged with the container and when tightened will form an effective baffle for the liquid content while permitting free air breathing.

Instead of making one of the cupped members polygonal for engagement with a wrench or turning tool, I may form it as shown in Fig. 8 in which the cup member C has a cylindrical portion C' of smaller diameter and wing portions C² extending diametrically from opposite sides thereof over the radially extending portion C³. This is adapted to be engaged by the fingers of the hand for screwing it into or out of engagement with the member to be capped instead of requiring a wrench.

What I claim as my invention is:

1. A screw cap comprising two pressed sheet metal cupped members, each having a radially outwardly projecting annular flange at its open end with the flange of one return bent over the other to form a three ply annular abutment the cupped portions of each member extending in the opposite axial direction from the other, one of said members being fashioned to form a hold for the turning of the same, and the other member being generally cylindrical and screw threaded on the outer surface and unthreaded on the inner surface with its bottom portion concave on the exterior and convex on the interior, and a plurality of struck out portions arranged to form narrow segmental slits near the periphery of the concave bottom, whereby any liquid gaining entrance through said slit will drain off from said convex surface and out again through said slits, each of said struck out portions also forming a shield guarding the corresponding slit against entrance of splashed liquid.

2. A plug for retaining a liquid within a container comprising two pressed sheet metal cupped members extending in opposite axial directions, each having a radially outwardly projecting annular flange at its open end with the flange of one return bent over the other to form a three-ply annular abutment, one of said members having a cylindrical portion extending from its flange with an integral bottom portion convex on the interior and concave on the exterior, the inner surface of said cylindrical portion being smooth and unthreaded, the outer surface of said cylindrical portion being screw threaded from the bottom to said three-ply annular abutment, said integral bottom portion having a plurality of struck out portions forming narrow slits opening at the outer circumference of said convex bottom, and the other of said cupped members having a polygonal portion forming a hold for turning the plug.
